UNITED STATES PATENT OFFICE

ALEXANDER A. MARKS, OF PHILADELPHIA, PENNSYLVANIA

WATER HEATER

Application filed November 22, 1922. Serial No. 602,591.

My invention is designed to provide means whereby fluid can be heated efficiently by waste products of combustion through intimate contact with extended surfaces exposed to the action of the heating gases. In its preferred form, it comprises a casing with undulated exterior walls and having internal flues alternating with the exterior fissures or sulci between the lobes or ridges formed by the wall undulations. The undulated walls and the internal flues passing through the expanded sections of the casing form sinuous channels for the flow of fluid, preferably transverse to the direction of flow of products of combustion passing through the internal flues and external fissures. Such casing is preferably combined with a plurality of hollow primary heating units having between them passages through which products of combustion are discharged from a combustion chamber to the flues and fissures of the casing.

Water heaters embodying my improvements are particularly adapted for use in preheating water applied to a heating system or for heating an auxiliary supply of water, as for household use or the like.

The characteristic features of my improvements will more fully appear from the following description of a preferred embodiment thereof and the accompanying drawings in illustration of the same.

In the drawings, Fig. 1 is a sectional elevation of a boiler having applied thereto water heaters embodying my invention; Fig. 2 is a sectional side elevation of the upper portion of the same; Fig. 3 is an enlarged horizontal sectional view through the heater shown in Figs. 1 and 2; and Fig. 4 is an enlarged fragmentary side elevation of a modification illustrating the connection of casing sections.

In the drawings, there is illustrated a boiler comprising hollow water heating elements 1 connected by nipples 2 and 3, the parts 1 being recessed to form a combustion chamber 4 and spaced to provide baffled passages 5 for the discharge of heated products of combustion from the fuel burner 6. 50 A heat insulating casing, comprising spaced

walls 7 and 8 with dead air space between them, surrounds the boiler elements and forms, above the units 1, a chamber 9 to which products of combustion are discharged after passing through the baffled 55 passages 5. A feed water conduit 10 is connected with the boiler below the burner 6 and a discharge conduit 11 is connected with the upper portion of the boiler.

A supply pipe 12 is connected with the 60 conduit 10 through a heater comprising a casing having undulated vertical walls forming protuberances or lobes 13 separated by the fissures or sulci 14, the inner portions of the undulations forming the walls 65 of channels 15 connecting the chambers 16 formed by the expanded sections of the casing. In the form shown, the casing has the flat parallel horizontal walls 17 through which pass fire tubes or flues 18 of elliptical 70 cross section, such flues extending across the chambers 16 so that fluid passing therethrough is baffled by the flues and obliged to follow the undulations of the exterior walls, providing a circuitous passage with a large 75 expanse of surface exposed to the waste heating gases discharged into the chamber 9 and therefrom into the chimney 19 at the top of the chamber.

The heater casing is symmetrical with respect to the center line thereof, and is provided at one end with an off-center hollow boss 20 having a threaded inner wall whose lower section is below the bottom wall of the heater, and at the opposite end with an off-center hollow boss 21 having a threaded inner wall whose lower section is above the bottom wall of the heater. Nipples 23 screwed into these bosses extend through the walls 7 and 8 and have connected therewith elbows 10' and 12' of the conduits 10 and 12.

A heat spreader and insulating shield 24, interposed between the tops of the elements 1 and the heater casing, prevent absorption 95 of heat by the preheater from the more highly heated fluid in the elements 1 and disperses the heated gases over the extended surfaces of the convolutions and flues of the heater casing.

A second heater casing 25, similar to the one above described but of less vertical depth, is disposed in the chamber 9 with its flues and fissures in registration with the flues and fissures of the preheater, and is connected with the pipes 26 of a supplementary heating system, as for instance, a hot water system for household use.

It will be understood that fluid supplied by the pipe 12 passes through the circuitous channels formed by the convoluted walls and flues of the preheater, being thereby brought into intimate contact with heating surfaces exposed to the action of the products of combustion passing from the burner 6 and combustion chamber 4, through the baffled passages 5 to the chamber 9, through the flues 16 and fissures 14 of the preheater, through the flues and fissures of the supplementary heater 25 to the chimney 19. The fluid heated in the preheater is discharged into the conduit 10 and elements 1 beneath the burner 6. As the fluid rises in the elements 1, it is exposed to the primary action of the heating gases and is discharged through the conduit 11 to radiators, whence it returns through the conduit 12.

The arrangement and position of the inlet and outlet bosses prevents clogging of the heater by accumulation of scale or sediment adjacent to the outlet, and permits the use of casings of the same pattern in boilers regardless of the direction of flow of the fluid, as the mere reversal of the casing will bring the lower boss at the discharge end.

If desired, the heater may be made in sections and similar ends of such sections connected by the insertion of a short nipple 27 in the corresponding bosses, as shown in Fig. 4.

Having described my invention, I claim:

1. A boiler comprising a plurality of hollow elements recessed to form a combustion chamber and having passages between them to which products of combustion are discharged from said chamber, and a heater disposed above said passages and comprising a casing forming chambers with a plurality of substantially straight vertical flues passing therethrough and a plurality of external vertically extending fissures between the walls of said chambers.

2. A boiler comprising a plurality of hollow elements recessed to form a combustion chamber and having between them vertically extending passages to which products of combustion are discharged from said chamber, a heater disposed above said passages and comprising a casing having undulated exterior walls forming chambers, baffles disposed in said chambers and passages for products of combustion substantially parallel with the passages first named to provide a circuitous passage through said casing,

and a heat spreader and insulator disposed between said elements and heater.

Signed at Philadelphia, in the county of Philadelphia, and State of Pennsylvania, this 18th day of November, 1922.

ALEXANDER A. MARKS.
